UNITED STATES PATENT OFFICE.

HAROLD JAMES PAYN, OF WEYBRIDGE, ENGLAND, ASSIGNOR TO VICKERS LIMITED,
OF WESTMINSTER, ENGLAND.

AUTOMATIC GUN CARRIED BY AIRCRAFT.

Application filed January 19, 1928, Serial No. 247,847, and in Great Britain January 19, 1927.

This invention relates to automatic guns carried by aircraft and of the kind provided with a cocking and loading lever which is under the control of the gunner and serves 5 when actuated to reproduce the movements of the barrel and the gun mechanism which occur during firing so that the gun can be initially cocked and loaded and can also be cocked and reloaded in the event of a cartridge misfiring, this operation causing the defective cartridge to be extracted and ejected. Cocking and loading levers of this type are quite effective for the purpose for which they are designed but they cannot 10 remedy a breakdown in the firing of the gun which occurs in the event of the gun mechanism not returning to the firing position owing to an oversize cartridge which cannot normally be caused fully to enter the cartridge chamber of the barrel.

According to the present invention the cocking and loading lever is associated or provided with an auxiliary member so constructed and arranged that when the said 15 member is operated in the reverse direction to that given to the lever in cocking and loading the gun, the said member will strike a downward blow upon the crank handle of the gun so as to force the lock into its forward or firing position and thereby insert the oversize cartridge fully into the cartridge chamber of the barrel. This auxiliary member is preferably in the form of a pivoted curved lever so shaped as to leave between it 20 and the operating part thereof a clear space for the normal movements of the crank handle during the firing of the gun. The said auxiliary lever may be provided with an operating handle and with a projection which operates with the aforesaid cocking and loading lever so that when the auxiliary lever is operated in order to effect the cocking and loading of the gun under normal conditions, the said auxiliary lever and the cocking and loading lever move together and when released are returned by a spring to the normal position, whilst when a jam due to an oversize cartridge has to be remedied the auxiliary lever is moved in the reverse direction 25 relatively to the cocking and loading lever so as to cause its end to strike a sharp blow upon the crank handle in order to force the

oversize cartridge into the cartridge chamber of the barrel. A spring may be provided between the auxiliary lever and the cocking and loading lever in order to return the auxiliary lever to its normal position when the gunner releases it. Instead of the auxiliary lever being pivoted to the cocking and loading lever, these two levers may be rigidly connected together.

In order that the said invention may be clearly understood and readily carried into effect, the same will now be described more fully with reference to the accompanying drawings, in which:

Figure 1 is a side elevation showing one form of cocking and loading lever and its associated auxiliary member in accordance with this invention, and

Figure 2 is a rear elevation of Figure 1. A represents in outline and in chain lines the rear part of the mechanism casing of a gun which is of the Vickers type having a crank handle A¹ the crank shaft A² of which is connected in the usual manner to the lock of the gun. This crank handle has the usual tail piece A³, the usual boss A⁴ and the usual hand knob A⁵. B represents the cocking and loading lever which is pivotally mounted on a fixed pin B¹ carried by the rear lower part of the mechanism casing. This cocking and loading lever is that known as the "Hyland" cocking and loading lever and is described in the specification of British Patent No. 126,670; it has a front part B² for engaging with the knob A⁵ of the crank handle A¹ and a curved projecting part B³ for engaging with the boss A⁴ of the said crank handle, so that when the said cocking and loading lever is moved in an anti-clockwise direction the crank handle is first moved angularly in a similar direction and is then moved rearwards bodily whilst having a further angular movement given to it, thus reproducing the cocking and loading movements of the gun. The return of the lever B to its normal position is effected or assisted by means of a spring B⁴ and in this position a projection B⁵ on the said lever bears against the rear face of the mechanism casing.

C represents the foresaid auxiliary member which in the example shown, is in the form of a curved lever pivoted coaxially with

the pin B¹ and is normally held in the position shown in Figure 1 by a spring C¹ operating between the two levers to hold a projection C² on the lever C against the rear surface of the lever B. The auxiliary lever C has an operating handle C³ which is shown as being detachably connected thereto and capable of being attached in any one of three positions. For this purpose the handle is formed with a slot C⁴ to receive a bolt C⁵ passing through a hole in the lever C and also to receive one or another of three pins C⁶ projecting at different positions from the lever C. Thus the handle C³ can be held in the position shown or in either of two other positions in which the slot C⁴ receives another pin. The lever C is so shaped as to leave between it and the operating part of the lever B a clear space for the movements of the 20 crank handle A¹ during the working of the gun and its free end is so situated that it can strike the knob A⁵ of the crank handle when it is necessary to force the lock of the gun mechanism into its forward or firing position by overcoming the friction due to an oversize cartridge. To effect this operation the handle C³ is moved in a forward direction, thereby angularly moving the lever C in a clockwise direction about the axis of the pin B¹. The 30 spring C¹ is extended during this movement and the projection B⁵ prevents the lever B from moving, this spring serving to return the lever C to its normal position when the handle C³ is released. The lever B is operated to perform its ordinary function by moving the handle C³ rearwards, the said lever B being moved through the intermediary of the projection C², and the spring B⁴ serves to return both the levers to their normal position when the handle C³ is released.

Instead of the lever C being pivotally arranged it and the lever B may be rigidly connected together in which case the spring C¹ would, of course, not be necessary and the projection B⁵ would not be provided as the lever B would then move downwards with the lever C.

What I claim and desire to secure by Letters Patent of the United States is:—

50 1. In an automatic gun having a cocking and loading lever under the control of the gunner and serving when actuated to reproduce the movements of the barrel and the gun mechanism which occur during firing; an auxiliary member movable in a direction opposite that of the lever in cocking and loading the gun to strike the crank handle of the gun and thereby cause the lock to be forced into its forward or firing position so as to insert an oversize cartridge fully into the cartridge chamber of the barrel.

2. In an automatic gun having a cocking and loading lever under the control of the gunner and serving when actuated to reproduce the movements of the barrel and the

gun mechanism which occur during firing; a pivoted curved lever shaped to leave a clear space for the normal movements of the crank handle of the gun during the firing thereof between it and the operating part of the cocking and loading lever, said lever being movable in a direction opposite that of the lever in cocking and loading the gun to strike the crank handle of the gun and thereby cause the lock to be forced into its forward or firing position so as to insert an over-size cartridge into the cartridge chamber. 70

3. In an automatic gun having a cocking and loading lever under the control of the gunner and serving when actuated to reproduce the movements of the barrel and the gun mechanism which occur during firing; a pivoted curved lever shaped to leave a clear space for the normal movements of the crank handle of the gun during the firing thereof between it and the operating part of the cocking and loading lever, said lever being movable in a direction opposite that of the lever in cocking and loading the gun to strike the crank handle of the gun and thereby cause the lock to be forced into its forward or firing position so as to insert an over-size cartridge into the cartridge chamber, said curved lever having a projection which cooperates with the cocking and loading lever to cause said levers to move together to effect cocking and loading of the gun, and means for operating said curved lever to effect said cocking and loading of the gun. 80

4. In an automatic gun having a cocking and loading lever under the control of the gunner and serving when actuated to reproduce the movements of the barrel and the gun mechanism which occur during firing; a pivoted curved lever shaped to leave a clear space 85 for the normal movements of the crank handle of the gun during the firing thereof between it and the operating part of the cocking and loading lever, said lever being movable in a direction opposite that of the lever in cocking and loading the gun to strike the crank handle of the gun and thereby cause the lock to be forced into its forward or firing position so as to insert an over-size cartridge 90 into the cartridge chamber, said curved lever having a projection which cooperates with the cocking and loading lever to cause said levers to move together to effect cocking and loading of the gun, means for operating said curved lever to effect said cocking and loading of the gun. 95

4. In an automatic gun having a cocking and loading lever under the control of the gunner and serving when actuated to reproduce the movements of the barrel and the gun mechanism which occur during firing; a pivoted curved lever shaped to leave a clear space 100 for the normal movements of the crank handle of the gun during the firing thereof between it and the operating part of the cocking and loading lever, said lever being movable in a direction opposite that of the lever in cocking and loading the gun to strike the crank handle of the gun and thereby cause the lock to be forced into its forward or firing position so as to insert an over-size cartridge 105 into the cartridge chamber, said curved lever having a projection which cooperates with the cocking and loading lever to cause said levers to move together to effect cocking and loading of the gun, means for operating said curved lever to effect said cocking and loading of the gun. 110

5. In an automatic gun having a cocking and loading lever under the control of the gunner and serving when actuated to reproduce the movements of the barrel and the gun mechanism which occur during firing; a pivoted curved lever shaped to leave a clear space 115 for the normal movements of the crank handle of the gun during the firing thereof between it and the operating part of the cocking and loading lever, said lever being movable in a direction opposite that of the lever in cocking and loading the gun to strike the crank handle of the gun and thereby cause the lock to be forced into its forward or firing position so as to insert an over-size cartridge 120 into the cartridge chamber, said curved lever having a projection which cooperates with the cocking and loading lever to cause said levers to move together to effect cocking and loading of the gun, and means for returning the auxiliary lever and the cocking and loading lever to their normal positions. 125

5. In an automatic gun having a cocking and loading lever under the control of the gunner and serving when actuated to reproduce the movements of the barrel and the gun mechanism which occur during firing; a pivoted curved lever shaped to leave a clear space 130 for the normal movements of the crank handle of the gun during the firing thereof between it and the operating part of the cocking and loading lever, said lever being movable in a direction opposite that of the lever in cocking and loading the gun to strike the crank handle of the gun and thereby cause the lock to be forced into its forward or firing position so as to insert an over-size cartridge into the cartridge chamber. 135

handle of the gun during the firing thereof between it and the operating part of the cocking and loading lever, said lever being movable in a direction opposite that of the lever 5 in cocking and loading the gun to strike the crank handle of the gun and thereby cause the lock to be forced into its forward or firing

position so as to insert an over-size cartridge into the cartridge chamber, and a spring connecting the auxiliary lever and the cocking 10 and loading lever for returning the auxiliary lever to its normal position.

HAROLD JAMES PAYN.
